Primary Examiner — John R Yeh*(74) Attorney, Agent, or Firm* — NSIP Law(57) **CLAIM**

We claim the ornamental design for a dishwasher, as shown and described.

DESCRIPTION

FIG. 1 is a front perspective view of a dishwasher showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is a cross-sectional view taken along line 9-9 of FIG. 2; and,

FIG. 10 is an enlarged view of the encircled portion in FIG. 9.

The broken lines in the figures depict portions of the dishwasher which form no part of the claimed design.

The dot-dash broken lines encircling portions of the claimed design that are illustrated in enlargements form no part of the claimed design.

1 Claim, 10 Drawing Sheets(56)
